(57) **CLAIM**

The ornamental design for a chassis for a radio control model car, as shown and described.

DESCRIPTION

FIG. 1 is a front elevational view of a chassis for radio control model car in accordance with my invention thereof;

FIG. 2 is a rear elevational view thereof;

FIG. 3 is a left side elevational view thereof;

FIG. 4 is a right side elevational view thereof;

FIG. 5 is a top elevational view thereof;

FIG. 6 is a bottom elevational view thereof; and,

FIG. 7 is a perspective view of a chassis for radio control model car.
